HYPODERMIC SYRINGE

Gordon D. Billingsley, Los Altos, Calif.

Application June 2, 1947, Serial No. 751,742

4 Claims. (Cl. 128—173)

1

This invention relates to hypodermic syringes and, more particularly, to improvements in hypodermic syringes of the character adapted to inject liquid medicaments intramuscularly or subcutaneously.

It is an object of the present invention to provide a hypodermic syringe adapted to be utilized to inject liquid medicaments of relatively high viscosity intramuscularly or subcutaneously with minimum trauma to the body tissues in which the needle of the syringe is injected.

Certain liquid medicaments, such as penicillin, are often administered hypodermically in a medium of beeswax and peanut oil, or similar substances, to prolong the action of the medicament after injection and are difficult and dangerous to administer by conventional, manually operable hypodermic syringes without painful and injurious movement of the hypodermic needle embedded in the patient's flesh, in view of movement of the needle caused by the necessity of exerting manual pressure of a high order against the plunger of the syringe to expel the medicament. It is, therefore, a specific object of the present invention to provide a hypodermic syringe adapted for injection of liquid medicaments of relatively high viscosity into the flesh of the patient without resultant pain and injury caused by movement of the inserted needle.

It is a further object of the present invention to provide a syringe constructed and assembled to maintain sterility of the medicament ejected therefrom into a patient.

It is a further object of the present invention to provide a hypodermic syringe having a disposable needle part.

It is a specific object of the present invention to provide a hypodermic syringe, comprising a self-contained actuating means whereby liquid medicaments of relatively high viscosity may be injected into the flesh of the patient with a minimum of movement of the injected needle on the part of the operator and, more specifically, to provide a hypodermic syringe provided with a gas-producing medium, selectively operable to inject a liquid medicament into the flesh of the patient without undesired movement of the injection needle.

It is a further and more specific object of the present invention to provide a hypodermic syringe adapted for injection of relatively high viscosity medicaments, of the character of penicillin dissolved in oil and wax, contained in a sterile cartridge or package.

A further object of the present invention is to

2

provide a hypodermic syringe of the character mentioned of relatively low cost, simple construction, and which is easy of operation and subject to strictest standards of sanitary maintenance.

Other objects and advantages will become apparent upon reference to the specification and accompanying drawings, in which similar characters of reference represent corresponding parts in the several views.

Referring to the drawings:

Fig. 1 is a longitudinal, sectional view of the syringe before actuation thereof.

Fig. 2 is a longitudinal, sectional view of the syringe after a liquid medicament has been ejected therefrom.

The invention comprises, essentially, a hypodermic syringe containing a gas-producing medium, adapted for selective actuation in order to expel a liquid medicament from a sanitary container through a tubular hypodermic needle into the flesh of the patient after the said needle has been initially properly positioned.

Referring to the drawings, the device comprises a cylindrical, tubular casing member 2, provided with suitable exterior threads at its upper end to receive threadedly a cap 3 provided with a central bore 4 to receive slidably the shank 5 of an operating trigger 6. The opposite end of casing 2 is provided with an aperture to receive a plug 7 in liquid-tight relation thereto. The plug 7, in turn, carries a tubular injection needle 8, of conventional type, embedded in said plug and immovable relatively thereto. The needle 8 is provided with a flesh-piercing point 9, at one end, and a piston-piercing point 11, at the end opposite thereto. The end 11 projects above the plug 7 and within the body of the syringe for a purpose hereinafter described.

Positioned removably and slidably within the casing 2 is a second cylindrical, tubular casing 15, which extends from top to bottom of casing 2. The inner casing 15 is provided with a vent aperture 16 approximately medially thereof for a purpose hereinafter described. Seal 17, formed of rubber or the like, having a hole provided centrally therein to receive slidably the shank 5 of trigger member 6, is disposed movably within the said secondary casing adjacent to the top thereof. The rubber seal 17 forms a fluid-tight connection at the top of secondary casing 15.

Disposed below the seal piece 17 is a piercing element 18 movable slidably within the member 15. Below the piercing element 18 and adjacent to the piercing portion thereof is a chemical disk portion 19, formed of sodium bicarbonate or

3

other suitable chemical, adapted to combine with another chemical contained in a capsule 20 to produce gas. I have found that a liquid chemical such as dilute hydrochloric acid contained in a suitable acid-resistant capsule, which said capsule is easily punctured by the piercing element 18, is suitable for the herein described purposes. As illustrated in the drawings, a second chemical disk 21 is provided immediately below the capsule 20 and is formed of the same chemical as disk 19. Obviously, many combinations of chemicals are adapted for use in my invention as a gas-forming means. For example, disks formed of carbide can be substituted for the sodium bicarbonate disks and a capsule containing water for the hydrochloric acid, as herein described. Further, it is contemplated that a cartridge containing a compressed gas, such as carbon dioxide, may be substituted for the disks 19 and 21 and capsule 20, which said cartridge is positioned and formed to be punctured or broken by the piercing element 18 upon movement of the trigger element longitudinally of the casing 2. It may be noted at this point that the piercing element 18 may comprise a part of the seal 17 or may be, as herein illustrated, a separate element.

Disposed below the gas-forming chemical or chemicals is a rubber piston 25, positioned in fluid-tight, slidable relation with the secondary casing 15. Preferably, the piston 25 is formed of soft rubber or similar suitable material and provided with a central well portion 26, the open end of which is disposed adjacent to the gas-forming chemical or chemicals, so that when gas is produced within the area in which the gas-forming chemical or chemicals are contained, the said gases will force the said piston 25 downwardly and simultaneously urge the piston into gas-sealing position with regard to the interior of the cylindrical casing 15.

Positioned below the piston 25 is a spacer member 27, illustrated here as a tube formed of glass or plastic or other suitable, preferably non-resilient substance. Below the spacer member 27 is disposed a piston 28 of the same character mentioned with respect to piston 25 and which is slidable within the cylindrical casing 15. Spaced below piston 28 is another identical piston 29, and, in a chamber 31, defined by pistons 28 and 29 and casing 15, is contained the liquid medicament 32.

It is to be noted that, in accordance with conventional practice, the pistons 28 and 29, provided with well portions 28a and 29a, respectively, are disposed facing the medicament contained therebetween. The point 11 of needle 8 is disposed immediately below piston 29.

A chamber 34 is provided between plug 7 and the bottom of piston 29, within which chamber the piston-piercing portion of the needle projects. It is to be noted that the casing 2 and the inner casing 15 may be formed of any suitable material, but it is incumbent that, insofar as chamber 34 is concerned, visual access through casings 2 and 15 be provided at that region for the reason that upon injection of the needle 8 into the flesh of a patient a means must be provided to determine whether or not the said needle has punctured a blood vessel. For example, in the administration of certain drugs, such as penicillin dissolved in oil and wax, the needle is initially positioned in the flesh of the patient and, if a blood vessel is entered, blood escapes through the tubular needle into the chamber 34 thereby warning the user of the syringe of the

4

position of the needle before injection of the drug to be administered. The provision of visual access within the syringe adjacent to the injection needle 8 is important in that certain drugs can not be injected, without ill effects, into a blood vessel.

The inner casing 15, together with associated medicament chamber 31, spacer member 27, piston 25, seal 17, piercing element 18 and gas-forming chemicals, may be formed as a unit for package insertion in the casing 2, which said casing 2 may be adapted for re-use. On the other hand, the package insertion may comprise merely the said casing 15, provided with a vent 16 and a medicament disposed therein between pistons 28 and 29. In the latter case, the spacer member 27, piston 25, gas-forming chemical or chemicals, piercing element, seal piece and trigger may be arranged within the casing 2 by the user of the syringe. It is to be noted that needle 8 and plug 7, in which it is embedded, are adapted for removal and disposal after each injection. The vent 16 is disposed approximately medially of the inner casing 15 for escape of gas produced by the gas-producing chemicals therethrough after the piston 25 has been depressed by the gas to a point below the said vent (see Fig. 2). The gas may escape to atmosphere through vent 16 and thence through vent 36 provided in the outer casing 2 in register with the said vent 16.

In operation, the needle is positioned in the flesh of the patient and, after determining that the needle is properly positioned, i. e. visual examination of chamber 34 to determine that no blood is passing thereto, the trigger 6 is depressed manually, thereby moving the seal 17 connected thereto, against the piercing element 18. The piercing element 18, which abuts against or is formed as a part of the seal 17, punctures the gas-producing capsule or cartridge 20, thereby instigating the chemical reaction adapted to produce gas and the resultant gas pressure which moves the piston 25 against the spacer member 27 and causes piston 28 to be depressed against the medicament 32 contained in the chamber 31. Pressure of piston 28 against the medicament 32 causes the piston 28 to move downwardly against point 11 of needle 8, thereby puncturing the same. Continued movement of the piston 28 downwardly causes the liquid medicament to be discharged into the tubular needle 8 for desired injection into the patient. The position of the various parts after operation, assuming the piercing element to be unattached to the seal 17 and the gas-forming chemicals to have dissipated, is indicated in Fig. 2.

The preferred embodiment of the present invention enables removal of the inner casing 15 and parts contained therein from the outer casing 2 as a unit. Further, the plug 7 and needle 8 may be removed easily from the casing 2 for convenient disposal.

The assembly of the unit may comprise the steps of, first, inserting the needle and plug in nested position in the bottom of casing 2; then, inserting the inner casing 15 containing the liquid medicament, spacer member, piston 25, gas-producing chemical or chemicals, piercing element 18 and seal 17; and, then, positioning the cap 3 and associated trigger on the outer casing.

It is to be noted that conventional means may be provided to induce flow of blood through the needle into the syringe interior after initial positioning of the said needle in the flesh. Conven-

tional means presently in use comprises a diaphragm member, or the like, adapted to accelerate the otherwise rather slow flow of blood into a syringe, and is obviously sometimes desirable for the purpose of accelerating the operation of the drug administration.

It is noted that the pistons disclosed herein are of the character to provide a fluid-type seal with the cartridge or inner tubular casing with which they may be associated, in order to prevent effectively the passage of gas therebeyond.

The outer casing may be formed of a suitable plastic substance or glass or metal, while the inner casing is, preferably, formed of glass. Obviously, the various parts may be formed of materials found to be suitable in the economic manufacture of the device and I do not intend to limit myself to the specific materials herein mentioned. Again, the arrangement of the several parts herein set forth in particular detail for the purposes of clarity of example and description, is not intended as a limitation as various changes, modifications and variations may be practiced and are intended to be practiced within the spirit of the invention and the scope of the appended claims.

I claim:

1. A hypodermic syringe comprising an outer tubular casing, an inner tubular casing slidably disposed within said outer casing, a tubular injection needle removably disposed within said outer casing and having a portion thereof projected into an end of said inner casing, a liquid medicament contained within said inner casing between spaced members slidably relative to said inner casing, another member slidably disposed within said inner casing and spaced from said liquid medicament, gas-forming means contained in said inner casing, and means comprising a trigger to actuate said gas-forming means whereby gas pressure is produced within said inner casing to force said liquid medicament downwardly against said injection needle.

2. A hypodermic syringe, according to claim 1, and wherein vent means is provided to vent gas produced by said gas-producing means to atmosphere after said liquid medicament has been moved against said needle.

3. A hypodermic syringe comprising an outer tubular casing, an inner tubular casing disposed within said outer tubular casing, a tubular injection needle disposed in the lower end of said outer casing and having a piston piercing point projecting into the lower end of said inner tubular casing, a lower chamber in the lower end of said inner tubular chamber, said lower chamber being defined by the inner wall of said inner tubular chamber, by a lower movable piston and by an upper movable piston, said lower movable piston normally being spaced upwardly from said piston piercing point, an upper chamber in the upper end of said inner tubular chamber, said upper chamber being defined by the inner wall of said inner tubular chamber, by a lower movable piston and by an upper seal, the lower movable piston of said upper chamber being rigidly spaced from said upper movable piston of said lower chamber, a liquid medicament in said lower chamber, gas

forming chemicals in said upper chamber, and trigger means to actuate said gas forming chemicals to generate gas pressure, whereby the gas pressure so generated is exerted downwardly on said upper piston of said lower chamber in sequence first to urge the lower chamber downwardly thereby to cause said piston piercing point to pierce the lower piston of said lower chamber and second to expel medicament contained in said lower chamber through said needle.

4. A hypodermic syringe comprising an outer tubular casing, an inner tubular casing disposed within said outer tubular casing, a tubular injection needle disposed in the lower end of said outer casing and having a piston piercing point projecting into the lower end of said inner tubular casing, a lower chamber in the lower end of said inner tubular chamber, said chamber being defined by the inner wall of said inner tubular chamber, by a lower movable piston and by an upper movable piston, said lower piston normally being spaced upwardly from said piston piercing point, an upper chamber in the upper end of said inner tubular chamber, said upper chamber being defined by the inner wall of said inner tubular chamber, by a lower movable piston and by an upper seal, a spacer member separating the lower movable piston of said upper chamber from said upper movable piston of said lower chamber, a liquid medicament in said lower chamber, gas forming chemicals in said upper chamber, an open vent in each of said inner and outer tubular members, the vent in said inner tubular member being located so that it is normally between the upper and lower chambers and so that it is above the lower piston of said upper chamber and communicates with the upper chamber when said interconnected pistons are at the lowermost point of their travel, trigger means to actuate said gas forming chemicals to generate gas pressure whereby the gas pressure so generated in sequence firstly is exerted downwardly to urge the lower chamber downwardly thereby to cause said piston piercing point to pierce the lower piston of said lower chamber, secondly is continued to be exerted downwardly to expel medicament contained in said lower chamber through said needle and thirdly is automatically vented to atmosphere after said liquid medicament has been discharged through said needle.
